UNITED STATES PATENT OFFICE

2,274,170

HAIR WAVING DEVICE AND PROCESS

Sinclair G. Stanley, Chicago, Ill.

Application July 8, 1941, Serial No. 401,443

10 Claims. (Cl. 132—36.2)

This invention relates to the art of permanent waving and apparatus or means for waving, curling and setting the hair, and more particularly, to permanent waving and hair curling and setting pads as a new article of manufacture and method of making or producing the same.

Heretofore in the art of permanent waving, curling, and setting hair it has been customary to use untreated sheets or pads, constituting a medium for holding and applying a softening, moistening and setting solution to the hair in connection with protectors or clamps for gripping and holding the curled hair as wound on the curlers, while subjected to the action of the heaters or clamps in which the chemical solution or treating liquid acts to set the curl or wave. But these, for example, consisted of sections of cloth, such as a folded piece of flannel sewed along one edge to a section or sheet of waxed paper together with a sheet of parchment or metal foil of aluminum, lead or tin on the outside. However, these pads are not only expensive and made doubly so by the demands on metal, but considerable time is consumed and lost in using the same. This results from the necessity of dipping or immersing the pads at the time of their use in a setting solution, and the time required in order to absorb same, due to the fact that they are too soft and flexible or flimsy and have a tendency to be water and liquid repellent or waterproof, non-bibulous or impervious initially and therefore difficult to handle as well as to saturate or impregnate with the treating solution or chemical.

The present invention overcomes these objections by providing an absorbent chemical pad of readily absorbent or bibulous character which will become readily saturated or impregnated with the chemical solution at one dipping and which is preferably in one section, piece or sheet which is relatively stiff to facilitate dipping and handling but becomes sufficiently flexible after dipping as to permit it to be readily applied, bent or fitted over the hair on the curlers to receive the heaters or clamps thereon by a simple one-step operation. The pad preferably consists of a rectangular section of relatively stiff absorbent or bibulous fibrous pressed cellulosic material, for example. This, for example, may be made from wood or cotton cellulose or rag pulp which will readily absorb or imbibe and retain for a time fluids or moisture preferably of a soft or spongy texture so as to become readily saturated or impregnated with the

solution but it may be of other suitable material.

In accordance with the present invention these pads are not only cheap but can be economically produced and used at a fraction of the labor and cost of the prior pads and may be preliminarily dipped in, impregnated or saturated with the treating or softening and setting solution or chemical and dried at once so that a large number may be prepared and dried at one time preferably after pressing out the surplus mixture or moisture while retaining the necessary chemical or solution in dry form and so supplied to the beautician or beauty parlor instead of requiring that the beauty operator take time to chemically treat the same. By this means, the pads may be treated and dried by machine in the plant or factory much more economically and it is merely necessary to dip the pads once in water when and as needed for use or application to the hair on the protectors and curler clamps as they readily absorb the water or other solution to form an aqueous mixture in solution with the chemical retained and carried in the pad which is impregnated or saturated therewith as supplied to the beauty parlor and then to apply the heaters or clamps thereto as usual. However, the pad will hold sufficient moisture to provide the necessary steam and sufficient liquid for evaporation purposes to soften the hair and change its form as desired.

Other objects and advantages to be attained will be hereinafter more fully described and pointed out with particularity in the appended claims.

The invention will be best understood by reference to the accompanying drawing, forming a part of this specification, and in which:

- 40 Fig. 1 is an end elevation of a protector and curler of the heater type as applied to the hair;
  - 45 Fig. 2 is a similar view, enlarged, and partly in section;
  - Fig. 3 is an enlarged plan view of a protector and clamp partly opened;
  - Fig. 4 is an enlarged view of a curler clamp partly opened;
  - Fig. 5 is a perspective view of an absorbent pad; and
  - 50 Fig. 6 is an elevation of a heating element or clamp.
- Referring to the embodiment of the invention as illustrated in the drawing, 10 designates a protector and clamp which has two jaws 11 and 12 pivotally connected as at 13 by an extension

of one jaw overlying the other jaw and adapting the jaws to be opened or closed for receiving a portion of the hair. Fastener 14 of any suitable type is provided at the opposite end of the protector in order to hold the jaws in clamping relation to the hair H against the head. The protector has a pad 15 such as rubber and felt to prevent injury and transference of heat to the head and scalp. One of the jaws such as the jaw 11 is provided with slotted bearings 16 to take a curler 17 having a rounded shank 18 at one end to permit it to turn in one of the bearings 16 while being retained against axial displacement by a squared head 19. The opposite end has squared shank 20 which fits in the opposite end bearing 16 and is held against turning thereby. However, before the squared shank 20 is inserted in the bearing, the hair is wound or coiled on the curler 17 and frictionally held against the jaws of the clamp when the curler is swung down to cause its squared shank 20 to engage the other bearing and is given a slight turn to tighten the hair thereon by a knurled head 21 outwardly of the squared shank 20, the hair being previously held on the curler by a clamping jaw 22 pivoted thereto as shown.

The permanent wave pad is designated at 23 and consists preferably of a rectangular section or sheet of absorbent or bibulous character which is relatively stiff to facilitate dipping and handling but becomes sufficiently flexible or pliable after dipping to permit it to be readily bent between the fingers and applied over the hair on the curler to receive the heater or clamp thereon by a simple one-step operation. It preferably consists of a fibrous section of relatively stiff or thick material which forms a pad which may be readily saturated or impregnated with the treating or chemical solution. For this purpose it may be some bibulous or absorbent material which will readily absorb or imbibe fluids or moisture and in this respect is of somewhat soft or spongy texture. This, for example, may be made as will be readily understood by those skilled in the art, of ninety per cent wood or cotton cellulose with the remainder the usual clay added for filler. It will be understood that the fibers may be cut quickly and short so as to avoid producing a gummy substance which would occur if the fibers were not cut quickly and short, to provide a loosely finished knit product.

As shown, 24 represents the long edge of the pad and 25 the short edge. In use, when the pad is applied to the protector and clamp, a clamp or heater is engaged thereover as in Figs. 1 and 2 and these clamps may be of the machineless or heatless type as well as the machine type shown in the drawing. They have spring held jaws 27 and 28, the spring being designated at 29 and pressure plates 30 preferably of fiber so that they can be handled without burning the fingers and in the machine type, wires 31 are employed for conveying current to the heating elements.

These pads may be cut to any size desired according to the nature of the curler, such as 2 1/2 inches by 3 inches. The pads are dipped in the proper treating solution and owing to the highly absorbent nature thereof may be dipped by machine at the plant or factory and then placed between rollers or otherwise pressed to remove surplus mixture or moisture and then dried to retain the chemical or treating solution in dry form with which the same has been thoroughly saturated or impregnated. By way of example,

the pad may be dipped in a solution of 25% ammonium carbonate or similar chemical with 75% of water by volume. Thus, when it is desired to use the pads in the manner previously described they are merely dipped in water and one dipping is usually sufficient so that the work of the beauty operator may be quickly carried on. This will provide steam while at the same time retaining sufficient liquid for evaporation purposes and to soften the hair and change its form in producing the desired curl or permanent wave. By having the surplus moisture pressed out of the pad in preparing same, they quickly dry and may be readily packed for shipment and are much more convenient to handle by the beauty operator when dry. However, they will retain sufficient chemical and a large number may be treated or dipped at one time and dried at once so that when needed for use it is only necessary to dip them in water in order to provide the necessary aqueous solution. Thus the pads may be produced at a fraction of the labor and cost of pads heretofore employed in this art. I also wish to have it understood that I do not desire to be restricted to any particular treating or chemical solution and that any hair softener may be employed, including one or more chemicals such as ammonium or potassium carbonate, sodium sulfate or other solution or chemical well known to the trade. In each instance the pads are dipped in water or an aqueous solution there-of containing ammonia or otherwise.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. As a new article of manufacture a hair curling and setting pad composed of a single sheet of paper pulp saturated with a treating solution.

2. As a new article of manufacture a hair curling and setting pad composed of a single relatively stiff sheet of unsized bibulous cellulosic material saturated with a treating solution in dry form.

3. A permanent wave pad or the like consisting of an absorbent sheet of unsized blotting paper impregnated with a hair softening and setting solution adapted to be dipped in water or aqueous solution on use.

4. A permanent wave hair curling and setting pad consisting of a relatively stiff section of bibulous material composed of unsized cellulosic material and a filler.

5. A permanent wave hair curling and setting pad consisting of a relatively stiff section of bibulous material composed of substantially ninety per cent cellulose pulp and substantially ten per cent clay holding a chemical or treating solution in suspension.

6. As a new article of manufacture, a wave pad for hair, a single sheet of highly absorbent unsized cellulosic material made from wood pulp and clay in dry form impregnated with a treating solution.

7. As a new article of manufacture, a permanent wave pad consisting of a single sheet of

paper pulp similar to blotting paper which has been dipped in a treating solution of ammonium carbonate and water and dried.

8. A hair curling and setting pad consisting of a sheet of unsized fibrous absorbent cellulosic material which has been dipped in a treating solution of about 25% ammonium carbonate and 75% water from which surplus moisture has been pressed and then dried to retain the chemical therein in dry form.

9. The method of making pads of the class described consisting in impregnating a section of unsized cellulosic material with a chemical or

treating solution of a carbonate and water for softening and setting the hair, pressing the same to remove surplus moisture and then drying.

10. A process of preparing permanent wave pads consisting in taking a sheet of relatively stiff absorbent unsized fibrous cellulosic material formed of paper pulp, dipping the same in a treating solution such as an aqueous solution of ammonia or the like for use, and drying the same to produce a pad in dry form impregnated with said solution for its subsequent dipping in water.

SINCLAIR G. STANLEY.
